UNITED STATES PATENT OFFICE.

FRED J. WARD, OF LONG BEACH, CALIFORNIA.

GAS FLOOR FURNACE.

Application filed April 28, 1926. Serial No. 105,126.

My invention is a gas floor furnace to be installed in the floor of a room or building structure in which the lighting and control of the gas is done from the floor level and the air to be heated is drawn downwardly from the floor and passed through the heater and discharged at the floor level.

An object of my invention is a floor gas furnace having a large radiating surface, by providing a central radiator above the burner or fire box and downwardly extending combustion passages spaced from the main radiator, whereby air may circulate around the main radiator and around the chambers for the products of combustion.

Another object of my invention is to provide a furnace of the type described, in which the cold air is drawn downwardly through an outer grate and discharged upwardly around the main radiator, and the products of combustion chambers, and discharged through a central grate.

Another object of my invention is to construct a floor furnace of such type that it may be readily cleaned, by providing a floor grate which may be readily removed, with a downwardly extending inner casing; thus allowing access to the casing bottom of the main or outer casing to allow cleaning.

Another object of my invention is to suspend the whole furnace construction from the floor by an outer casing and to confine the air to be heated within said casing, drawing the air to support the products of combustion from below the floor and outside of the casing.

In constructing my furnace I preferably make same rectangular in shape, of a greater length than width, providing a rectangular or box-like outer casing open at the top, this casing being suspended from the floor through a proper sized opening therein. A burner or fire box is supported on the bottom of the casing, the burner box being open at the bottom. An inner casing is suspended from the grate, extending around the opening in the floor and a radiator mounted on the burner box and chambers for products of combustion separate therefrom at each end, are housed in the inner casing. A dome or radiator top forms a gas-tight closure for the top of the radiator and the products of combustion chambers.

A cap with a transparent closure is centrally positioned in the dome so that the operation of the burner may be inspected.

and a central removable grate is positioned forming an outlet over the inner casing.

My invention will be more readily understood from the following description and drawings, in which:

Figure 1 is a plan view of the furnace, showing the grates and stationary plate attached to an opening in the floor;

Fig. 2 is a vertical longitudinal section of the furnace on the line 2—2 of Fig. 1, in the direction of the arrows, on an enlarged scale;

Fig. 3 is a horizontal section on the line 3—3 of Fig. 2, in the direction of the arrows, illustrating mainly part of the main radiator construction, the burner box and the products of combustion chambers, or as they may be designated, the supplementary radiators;

Fig. 4 is a plan view taken in the direction of the arrow 4 of Fig. 5, of the main radiator and the supplemental radiators with the dome or radiator top removed;

Fig. 5 is a side elevation of Fig. 4, taken in the direction of the arrow 5;

Fig. 6 is a plan view of the burner box and base, taken in the direction of the arrow 6 of Fig. 7;

Fig. 7 is a side elevation of Fig. 6, taken in the direction of the arrow 7;

Fig. 8 is a detail of the bottom closure of the supplemental radiators;

Fig. 9 is a horizontal section taken on the line 9—9 of Fig. 2, on a reduced scale, showing the dome or radiator top;

Fig. 10 is a perspective view of the outer casing;

Fig. 11 is a detail plan of the stationary control plate through which the stems of the main burner and pilot valves extend;

Fig. 12 is a cross section of Fig. 11, on the line 12—12 in the direction of the arrows;

Fig. 13 is a vertical detail section on the line 13—13 of Fig. 12 in the direction of the arrows;

Fig. 14 is a sectional vertical detail, illustrating the manner of suspending the outer and inner casings.

The outer casing and burner box construction is substantially as follows, having reference particularly to Figs. 2, 3, 6, 7, 10 and 14:

The outer casing 1 is rectangular, being the shape of the floor opening and preferably of greater length than width and formed with flat sides. The casing sides 2 have a flange 3 on the upper edge extending out

wardly, the flange engaging over the edge of the floor or other support for the furnace. A casing bottom 4 is preferably a casting and has a T-shaped flange 5 on the edge. 6 The lower edge of this flange engages an inwardly turned flange 6 on the casing walls.

7 A series of lugs 7 are utilized to bolt the casing bottom to the casing walls. The burner or fire box is designated generally by 10 the numeral 8 and has a lower flange 9 bolted to the casing bottom, there being an opening 10 in the bottom of proper size and shape to accomodate the burner box. This box is provided with a groove 11 at the top edge 15 and to support the main radiator as hereunder set forth.

16 The burners 12 are supported on vertical pipes extending from the horizontal pipes 13, these latter being supported by suitable 20 brackets. A pilot burner 14 extends upwardly between the main burners and is also connected to horizontal supply pipes. These pipes have valves 15 with stems 16 leading upwardly to valve handles 17; thus controlling the supply of gas from the feed 25 pipes 18.

19 An outer grate 19 rests on the floor, extending over the flange 3 and has a cut-out section in which is secured the control 30 indicator plate 20. This plate is illustrated particularly in Figs. 11, 12 and 13, the plate being formed angularly with a web 21 which is bolted to one side of the casing and has apertures 22 for the valve stems and handles 35 17.

40 The inner casing designated generally by the numeral 23 has vertical walls 24, these walls having an inward taper 25 at the top with a short vertical section 26 and an in-turned flange 27. This flange is supported on the outer register or grate as indicated particularly in Figs. 2 and 14. The inner casing is open at the bottom as indicated by the numeral 28 and has vertical slots 29 therein to accommodate the exhaust flues 30 which lead to a smoke pipe 31.

35 The radiator construction is substantially as follows, having reference particularly to Figs. 2, 3, 4, 5, 8 and 9:

50 The main radiator is designated generally by the numeral 32, having supplementary or auxiliary radiators 33 on the ends. The main radiator has corrugated side walls 34 with deep corrugations and curved end walls 35. These walls fit in the groove 11 on the upper edge of the burner box. The auxiliary radiators 33 have an inner curved wall 36 concentric with the curved wall 35, an outer wall 37 parallel to the ends of the 55 furnace, and side walls 38 parallel to the side walls of the furnace. These side walls are preferably on the line with the outer edge of the corrugations of the side 34 and connected to the flues 30. These flues are 60 connected above the level of the burners.

65 A closure plate 39 is secured to the lower end of the supplemental radiators, being held in place by rods 40 and are secured to a radiator cover or top plate 41. It will be noted that the top plate is somewhat arched 70 or dome shaped over the main radiator and has depressed end portions over the auxiliary radiators. The shape of this plate is illustrated particularly in Fig. 9, forming a gas-tight closure with the top of the main 75 radiator and of the supplemental radiators. An opening 42 for the products of combustion is formed by a downwardly curved transition plate 43 which joins the walls 35 and 36 leading upwardly to the top plate 80 41 on the edge; thus giving sufficient space to allow reversal of direction of the burnt gases from the burners.

85 The dome is provided with a circular flange 44 to which is fitted a cap 45 having a transparent window 46 and having a handle 47 to allow removal. This window allows inspection of the burners in order to see if they are burning properly and by removing the cap the pilot burner or the main 90 burner can be lit by inserting a match or the like held in a suitable holder. Tie bars 48 are utilized to secure the dome and the burner box tightly together, being bolted through a flange 49 on the upper 95 edge of the burner box. A central removable grate or register 50 is fitted on the flange 27 of the outer casing and may be bodily removed to allow access to the cap 45 for lighting the burners. 100

105 The manner of using my gas floor furnace and the functions of the different parts are substantially as follows:

110 It will be understood from the above description that my gas floor furnace may be installed in old as well as in new buildings, provided there is sufficient space underneath the floor for the installation. The outer casing with the casing bottom forms an air-tight chamber so that no air from below the floor may get into same, except the small amount which might pass around the valve stems 16. The burner base is firmly secured to the casing bottom, the burner extending upwardly into said base so that the air for consuming the gas is drawn from below the floor and does not draw air from the room being heated. 115

120 The main radiator has deep corrugations on opposite sides which transfer heat to the upwardly ascending air, this air being drawn downwardly into the furnace through the outer grate 19 and between the inner and outer casing. The end walls of the main radiator become very hot on account of 125 the products of combustion passing into the supplemental or auxiliary radiators 33 in which the products of combustion pass downwardly to the exhaust flues 30. On account of the space between these end walls 130

and the supplemental radiators, the air being heated is brought into intimate contact with these surfaces. The air on its upward passage strikes the curved transition plate 5 or inverted arch 43 and is forced sideways to opposite sides of the inner casing. The heated air therefore which passes around the main and the two supplemental radiators, passes upwardly and outwardly out 10 of the central grate or register 50.

If desired lugs 51 may be secured in the corner of the outer casing to which bolts 52 passing through the outer grates are secured, thus holding said grates in a firm 15 position. On removing said bolts the inner and outer gratings may be removed with the inner casing; thus giving access to a considerable part of the furnace, especially the casing bottom to allow cleaning. If 20 necessary ferrules 53 may be placed between the lower ends of the main radiators and the supplemental radiators between the walls 35 and 36 to hold the supplemental radiators in proper adjusted position.

25 My gas floor furnace is of a type which may be installed through an opening in a floor and is particularly adapted for houses where the climatic conditions are not so severe as to require large heating units, and 30 is of especial advantage where gas is relatively cheap, as in the neighborhood of oil fields, such as in some parts of California and Texas. This type of furnace is generally installed in houses which have no 35 basement, and therefore, the structural features which allow this to be assembled substantially completely while being placed in its permanent location are of considerable 40 commercial advantage. Moreover, the type of floor furnace illustrated has a large heating area for its size. By means of having the valves regulatable from the floor level, the regulation of the heat is easily accomplished.

45 It will also be noted, moreover, that with my construction properly built and installed, there is no opportunity for gas fumes to escape into the building.

An advantage in the art of my furnace in 50 having the auxiliary radiators at each end of the main radiator and spaced therefrom by the transition plate 43 is that a much larger surface of the radiators is exposed to the air to be heated with the products of 55 combustion passing through the interior of such radiators. Therefore, the temperature of the products of combustion at the outlet into the flues or vents leading to the stack may be much lower than when this construction is not used. This gives the effect 60 that a greater amount of heat is extracted from the products of combustion from the gas burners than when there are no auxiliary radiators with a distinct air space therebetween. Moreover, with the transition plate

65 43 forming an inverted arch, the air flowing up between the ends of the main and auxiliary radiators is not obstructed in the upward flow but is diverted to both sides, passing upwardly outwardly through the center 70 grate.

Another characteristic advantage of my invention is that the cover over the main radiator has a center part bulged upwardly with the parts over the auxiliary radiator 75 at a lower level so that the products of combustion passing upwardly from the burner box are given a downward deflection in both directions at the ends of the main radiator.

Another advantage of having the two 80 auxiliary radiators with the vent outlets therefrom is that in lighting the burners it is much easier to secure a proper draft on account of the vent openings being at opposite ends of the furnace and allowing the 85 products of combustion to be diverted in both directions at the top of the combustion chamber over the burners. The structural features of having the closure at the lower end of the auxiliary radiators supported 90 from the cover at the top facilitates the assembly of the furnace and the inner and outer walls of the casing being suspended from inner and outer sections of the grating at the top facilitates the installation of the 95 furnace in the floor of the building.

While I have described my gas floor furnace as being rectangular in shape, it will be understood that it may be made in any suitable shape desired, the arrangement described however being an economical manner of construction as it allows the use of flat sheets of metal. It is also manifest that the general construction and specific details of my floor furnace may be materially 100 changed to suit different types of constructions and installations. Such changes however, would be within the spirit of my invention as set forth in the description, drawings and claims.

Having described my invention, what I claim is:

1. A gas floor furnace comprising in combination an outer casing having side walls suspended from the floor, a casing bottom having a central opening with a burner box attached thereto, the burner box being open at the top and bottom, a main radiator supported on the burner box, a radiator top or dome connected thereto, supplementary radiators spaced from the main radiator by transition plates and being suspended from the dome, there being passages for products of combustion between the main and supplementary radiators at the top thereof, and vent pipes connected to the supplementary radiators.

2. A gas floor furnace as claimed in claim 1, the supplementary radiators having lower closure plates, the suspending means being

connected to said closure plates, and a spacing ferrule between the main and the supplementary radiators.

3. In a furnace a main radiator having a curved end wall, side walls with deep corrugations, a supplementary radiator spaced from the end wall by a transition plate and having a wall curved concentric to the end wall, the supplementary radiator having substantially straight sides on the rest of its periphery, there being a passage for products of combustion between the main and the supplementary radiator at the upper portion thereof.

4. In a gas furnace, a main radiator having outwardly curved end walls, deeply corrugated side walls, a radiator top plate resting on the upper edges of the said sides and ends, supplementary radiators having inner walls concentric with the curved outer ends of the main radiator and spaced therefrom by transition plates, the said supplementary radiators being secured to the said cover plate, there being passages for products of combustion between the main and supplementary radiators at the upper portion thereof, and vent pipes from the supplementary radiators.

5. In a gas furnace as claimed in claim 4, in which the supplementary radiators are each provided with a closure plate at their lower end, the said closure plate being suspended from the cover plate of the radiator.

6. A furnace having a burner box, a main radiator having vertical corrugations supported thereon, a cover plate connected to the main radiator, an auxiliary radiator connected to the main radiator at one end thereof and at the upper part by a transition plate, there being an air space distinct from the corrugations between the main and auxiliary radiators at the lower part thereof, and means to suspend the auxiliary radiator from the cover plate.

7. A furnace comprising in combination a burner box having a radiator with vertical corrugations on its side and having convex vertical ends, a cover plate secured to the top of the radiator, an auxiliary radiator spaced from the end of the main radiator by a transition plate and having an adjacent wall concentric to the end wall of the main radiator, said transition plate and cover forming a connection for the passage of products of combustion out of the upper part of the main to the auxiliary radiators, and means to suspend the auxiliary radiator from the said cover plate, there being an air space between the lower part of the auxiliary radiator and main radiator distinct from the corrugations.

8. A furnace comprising in combination a burner box having a main radiator with vertical corrugations on its side walls supported on said box, a cover plate secured to the top of the radiator, an auxiliary radiator on the end of the main radiator and spaced therefrom, the adjacent ends of the main and auxiliary radiators being concentric, a closure plate on the lower end of the auxiliary radiator, a transition plate forming an inverted arch making a connection between the adjacent walls of the main and auxiliary radiators, and means to suspend the auxiliary radiator from the cover plate, there being an air space between the lower part of the auxiliary radiator and main radiator distinct from the corrugations.

9. A gas floor furnace comprising in combination a supporting structure connected to a floor having a burner box thereon, a main radiator supported by the burner box, a cover plate secured to the top of the main radiator, a transition plate secured to the end wall of the main radiator, an auxiliary radiator connected to said transition plate and having its lower part separated by an air space from the end of the main radiator, said cover plate enclosing the upper end of the auxiliary radiator, and a closure for the lower end of said auxiliary radiator, there being a vent adjacent the lower end of said auxiliary radiator.

10. A gas floor furnace comprising in combination a supporting structure having a burner box, a main radiator mounted thereon and having a cover plate, a transition plate secured to the end wall of the main radiator, an auxiliary radiator attached to said plate, the cover plate extending over the auxiliary radiator, said plate having a dome section above the main radiator and a depressed end over the auxiliary radiator, a closure for the lower end of the auxiliary radiator, there being a vent adjacent to said lower end.

11. A gas floor furnace comprising in combination a supporting structure having a burner box therein, a main radiator mounted thereon and having vertical ends curved outwardly in horizontal section, a cover for the main radiator, a transition plate secured to the end of the main radiator, an auxiliary radiator connected to the transition plate and having a wall spaced from the curved end wall of the main radiator and concentric thereto, the cover plate forming a top closure for the auxiliary radiator, and a closure for the lower end of the auxiliary radiator with a vent adjacent thereto.

In testimony whereof I have signed my name to this specification.

FRED J. WARD.
